UNITED STATES PATENT OFFICE.

JOHN H. PENDLETON, OF BROOKLYN, ASSIGNOR, BY DIRECT AND MESNE ASSIGNMENTS, TO THE RAPID TRANSIT CABLE COMPANY, OF NEW YORK, N. Y.

TRACTION DEVICE FOR CABLE RAILWAYS.

SPECIFICATION forming part of Letters Patent No. 387,989, dated August 14, 1883.

Application filed August 6, 1885. Renewed June 13, 1888. Serial No. 276,929. (No model.)

To all whom it may concern:

Be it known that I, JOHN H. PENDLETON, of Brooklyn, in the county of Kings and State of New York, have invented an Improvement in Traction Devices for Cable Railways, of which the following is a specification.

This invention is for guiding the endless cable as it is raised and passed between the gripping apparatus, and for applying the power necessary to grip such cable gradually and start the car or to release the grip and stop the car.

In the drawings, Figure 1 is a general plan of the gripping device beneath the car, the position of the car to the same being indicated by dotted lines. Fig. 2 is a side view of the gripping apparatus. Fig. 3 is an elevation in smaller size of a car-truck, the lower part of a car, and the gripping device. Fig. 4 is a separate plan of the truck, a portion being broken off. Fig. 5 represents the guide-wheels on the truck for the cable, and Fig. 6 is a side view of the same. Fig. 7 represents the clamping-wheels endwise of the cable. Fig. 8 is a cross-section at or about the line $\alpha\alpha$ of Fig. 1, and Fig. 9 is an elevation of the divided cable-supporting wheel and the devices for holding the same. Fig. 10 is a plan of the parts, partially in section; and Fig. 11 is a vertical cross-section at line yy of Fig. 9.

A portion of the car is represented at A, and B B are the supporting-wheels in truck-frames c, which wheels and frame may be of any desired character, except that the truck-frame is to be adapted to the reception of the vertical grooved wheel D, that is upon a horizontal axis in the frame d', so that the rope or cable E will run along beneath and in contact with said wheel D; and F F are grooved rollers, with directing-cones upon their under surfaces, that serve to deflect or guide the cable in between themselves and into the groove in the wheel D. These rollers F are supported in the frame d', that is attached to the truck-frame C, and at each side of the center line of the truck are guide-plates k, with an opening between them that is sufficient for the cable to pass freely in when being raised up between the rollers F F. These guide-plates k are inclined

upwardly at the end portions, as shown, so 50 that there is no risk of the cable being caught or obstructed.

One of the peculiarities of this invention relates to the cable being lifted up into the clamping device under the middle of the car. 55 At the terminal stations each car is usually disconnected from that part of the cable going in one direction and switched into the desired place on the other track. There the car is connected to the part of the rope going in the 60 other direction by lifting said rope up into the clamping apparatus. When the rope is lifted by any suitable wheels and levers, it is raised up between the wheels F F and against the under side of the wheel D upon each truck, so 65 that the cable can be lifted high enough to be grasped by the grip, hereinafter described, and when the car is standing still or moving at a less speed than the cable the wheels D F F will revolve and prevent undue friction. 70 These wheels D prevent the cable running in contact with the axles of the trucks, and at the same time allow such cable to be bent upwardly sufficiently to reach and pass over the supporting-wheels K in front of 75 and behind the gripping apparatus. If these wheels K were made in one piece, there would be difficulty in passing the cable into the grooved periphery and in supporting the 80 wheels. I therefore make each wheel K in two parts, the division being perpendicular to the axis and in the bottom of the groove. I will describe one of these wheels K and its supporting devices, the second wheel, K', which is located at the other side of the gripping apparatus, being the same in its construction and mode of operation.

The halves k' k' of the wheel K are upon the ends of short shafts l' l' within tubular bearings k' k', and to these bearings the links l' l' 90 l' are connected, and these at their upper ends are pivoted to the under side of the car by the shafts l' and the bearing beams or flanges l' l', and in order to brace the links against lateral motion under the strain incident to 95 the cable running over the wheel K, I make use of the braces m, that extend down diagonally from such shafts l' to the sides of the links, as

seen in Fig. 11. It will now be understood that the parts of the wheel K can be separated by swinging the tubular bearings $k^6 k^7$ apart and carrying with them the respective halves 5 $k^2 k^3$ of the wheel, the links $l l' l' l$ allowing for this swinging movement, and in order to give motion to the parts and to hold them in either position to which they may be moved I employ any suitable set of cranks or links, 10 preferably those shown, wherein n is a rock-shaft running along the car and having an arm, n' , or lever at one end, to be operated by the attendant at the platform of the car, and n^2 is a crank-arm for one of the divided wheels, 15 K, and there is a crank-arm for the other divided wheel, K', and from these cranks pass to each swinging frame the links n^4 , being connected at 6 to the links $n^5 n^6$, so that when the shaft n is partially revolved and the pivotal connection 6 raised up the links $l l'$ will be pressed in one direction by the links n^6 and the links $l l'$ will be drawn in the other direction by the links n^5 , thereby swinging the tubular bearing $k^6 k^7$ apart, separating the two halves $k^2 k^3$ of 20 the wheel and allowing the cable E to drop. The reverse movement is to be given to the parts after the cable has been raised up between the two parts $k^2 k^3$ of the wheels and elevated above said wheels, so that the cable 25 will thereafter be supported by the wheels, the two parts being closed together, and in consequence of the pivotal connections between the links l^6 and n^6 and l' and n^5 being in line with the pivot 6 the two parts of the wheel K cannot 30 separate without some of the parts breaking, and in order to insure the proper position of the respective parts I provide upon the bearer l^6 a downward projection at l^6 , that occupies a central position between the links l^6 and l' , and against the sides of which such links $l^6 l'$ swing when the cable is supported by closing the two parts of the wheel K.

When the car is standing still, the cable E runs in a straight line over the wheels K K', 45 and between said wheels I apply the clamp or gripping apparatus, which is constructed as follows: Attached to the under side of the car are brackets P P, and there is a plate, P', passing across between these brackets and bolted 50 to their inner faces. The cross-shaft P^2 is in bearings in the brackets P P, and, passing through said brackets, receives upon its ends the gear-wheels p , and these gear into the respective wheels upon the ends of the screws 55 q' , hereinafter referred to. In order to rotate the shaft P^2 and the gear-wheels connected to the same, I make use of shafts $r r'$, extending to the respective ends of the car, so that the same can be rotated from either end of the 60 car by bevel-gearing R^2 and by a shaft, r^3 , to the upper end of which a hand-wheel is applied, and there are bevel-gears at R^5 to connect the shaft P^2 to the respective shafts $r r'$. By this arrangement of gearing the attendant 65 can apply the grip to the cable from either end of car or take off said grip. The screw-shafts

$q' q'$ are made with right and left handed screw-threads acting upon the grip-blocks $s s'$, which blocks are suspended from the plate P' by suitable screw-bolts, s^2 , and the plate P' is slotted for the passage of the bolts, so that the grip-blocks $s s'$ can be moved toward or away from the cable for gripping or releasing said cable. I also provide wheels placed in pairs at opposite sides of the cable. The wheels T 75 T are supported by brackets from the yoke-piece t , and the wheels T' T' are supported by brackets from the yoke t' ; so, also, the wheels T² T³ are supported by brackets from the yoke-pieces $t^2 t^3$, respectively, and the yoke-pieces $t t'$ are joined together by the equalizer u , and the yokes $t' t'$ are connected by the equalizer u' , and these equalizers are suspended beneath the plate P' by the bolts 3 in slotted holes in said plate, so that the equalizers can be moved 80 toward or from the cable and carry with them the pairs of wheels aforesaid to press upon the sides of the cable or to release the same.

Around the screws q' are the followers $v v'$, such followers being threaded to form nuts 90 around the screws, and between the followers and the equalizers $u u'$ are springs 5, there being guide-rods passing through the respective portions to keep the springs in place.

Each wheel T T' T² T³ is made with a grooved 95 periphery adapted to fit upon the side of the cable E, and there are, also, cylindrical portions of less diameter above and below the grooved portions, and the yoke-pieces $t t' t^2 t^3$ are adapted to press against the respective 100 cylindrical surfaces, the yoke-pieces being recessed for the reception of the grooved peripheries, and there are loose straps at 7, that prevent the respective rollers T T' T² T³ falling away from their proper positions. The 105 straps are connected at their ends to their respective yoke-pieces, and the equalizers $u u'$ are pivoted at their ends to the respective yoke-pieces, so that when either shaft r^3 is revolved the screws q' will be rotated by 110 the intermediate gearing and move the equalizers $u u'$ in either direction, according to the direction of the rotation of the hand-wheel upon the shaft r^3 . The construction of the 115 parts is such that the screws q' act upon the followers $v v'$ and bearers $u u'$ to bring up the pairs of wheels against the opposite side of the cable and grip the same upon the cylindrical portions of the respective wheels and start the 120 car forward, and then the further movement applies the gripping-blocks $s s'$; or, when the reverse movement takes place, the grip of the blocks $s s'$ is first liberated, and then the further movement draws back the pairs of rollers T T' T² T³, entirely releasing the hold upon the 125 cable.

This improvement is especially adapted to elevated railways where the cable runs between the tracks, and I am by this improvement enabled to drop the cable, if necessary, or to connect onto the cable after the cable has been 130 raised and placed into the apparatus.

I claim as my invention—

1. The combination, with an endless traveling cable and a gripping apparatus for the same upon the under portion of the car, of the wheel 5 D upon a horizontal axis, the wheels F upon a vertical axis and having conical projections upon their under sides, and the frame d', connected with the car-truck, substantially as and for the purposes set forth.
- 10 2. In combination with the car and its trucks, a gripping apparatus upon the bottom of the car, the guide-plates k k, inclined upwardly at their ends and connected with the truck-frame and the guide-roller D above such guides k, 15 and the frame d' for the same, connected with the truck-frame, substantially as set forth.
3. The wheel K, formed in two parts, each of which is provided with a supporting shaft, in combination with tubular bearings for the 20 shaft, the links for sustaining said tubular bearings, and mechanism, substantially as specified, for swinging the bearings to separate the two parts of the wheel or to bring the two parts of the wheel together and sustain the 25 cable, substantially as set forth.
4. The combination, with the two parts of the wheel K and the shafts for the same, of the bearings k' l', supporting-links l l' l' l', the bearing-bars l' l', the shafts l', the braces m, and the links n⁵ n⁶ n⁴, the shaft n, and crank 30 n², substantially as specified.
5. The combination, with the gripping-blocks s s', of the screws q' q', for actuating the same, the wheels p and p', the shaft P', the frames P, and plate P', and the gearing for giving 35 motion to the respective parts, substantially as set forth.
6. The grasping-wheels in pairs and the respective yokes for the same adapted to bear upon the cylindrical portions of the wheel, 40 the equalizers u u', connecting the respective pairs of yoke, the followers, and the springs between the followers and the equalizers, substantially as set forth.
7. The combination, with the gripping-blocks and the screws for actuating the same, of the clamping-wheels, the yokes and the equalizers for the same, the followers, and the 45 springs between the followers and the equalizers, and mechanism, substantially as specified, for rotating the screws, substantially as 50 set forth.

Signed by me this 3d day of August, A. D. 1885.

J. H. PENDLETON.
